UNDERGARMENT

Howard B. Snader, Reading, Pa.

Application September 29, 1932, Serial No. 635,437

1 Claim. (Cl. 2-237)

This invention relates to pants, bloomers or the like, constructed with a relatively wide encircling elastic band at the waist and around the leg openings. A garment of this type has 5 the distinct advantages over one provided with elastic cord bindings in that the pressure of the narrow binding is concentrated upon a small area of the flesh and is therefore, uncomfortable. The wide bindings distribute the same pressure over a greater area and therefore, the pressure per unit of area is less, and the garment is more comfortable in this respect.

Furthermore, the cord elastic is customarily run through a hem at the perimeters of the 15 openings, creating fullness in the garment at the extremities which shows objectionably through the outer apparel.

The wide band elastic, on the other hand, is usually stitched to the edges of the material of 20 the garment, and clings contractively to the body and legs, merging into the contour of the form without creating fullness.

As ordinarily constructed however, the wide band has the objection of heating the parts 25 which it overlies, causing perspiration, and the attendant discomfort. It is also apt to fold over in front upon flexion of the abdomen producing objectionable roll which may show through the dress.

One of the objects of the present invention is 30 to construct the pants, bloomers or the like, with relatively wide elastic bands at the waist line and leg openings made of open mesh rubber elastic webbing, the apertures of the meshes 35 affording ventilating openings, and which enlarge the more the elastic is tensioned, thus varying the ventilating capacity of the elastic according to the degree to which it is stretched.

Another object of the invention is the provision 40 in pants or bloomers of the type described of a waist band formed of relatively wide rubber elastic webbing so constructed that the top edge of the front portion is under greater tension when the garment is worn than the lower edge of the front portion, this effectively preventing rolling of the band.

Other objects of the invention will appear as 45 the following description of preferred and practical embodiments thereof proceeds.

In the drawing which accompanies and forms 50 a part of the following specification and throughout the several figures of which the same characters of reference have been employed to designate identical parts,

Figure 1 is a front elevation of a pair of ladies'

pants or bloomers embodying the principles of the present invention, the full line depiction of the waist band representing its position when on the person and the dotted lines representing its position of repose from which it is lifted 60 through stretching incident to the girth of the body which it encompasses;

Figure 2 is a front elevation of the same garment shown in Figure 1 when off the body;

Figure 3 is a perspective view of the waist 65 band in its reposed position; and

Figure 4 is a front elevation of a slightly modified form of elastic waist band.

Referring now in detail to the several figures, the numeral 1 represents in general the pants 70 comprising the body portion 2 which may be made of sheer or flimsy material such for example, as silk or rayon, the same being bound at the waist line with an encircling band 3 of rubber elastic webbing. Similar bands 4 and 75 5 are attached to the edges of the leg openings in the body portion 2.

It will be observed from Figure 3 that the elastic webbing constituting the bands 3, 4 and 5 is constituted by elastic rubber warp threads 80 6 extending circumferentially and being incorporated into crocheted lacework having the open meshes 7. These meshes have a ventilating function.

Since the waist band 3 is of elastic webbing, a 85 single size of garment is adapted to fit several sizes of waist line, the band being stretched more or less according to the girth of the waist which it surrounds. The waist band is so made that the open meshes 7 increase in area the 90 more the waist band is stretched, thus varying the ventilating capacity of the waist band according to the degree to which it is stretched.

In order to prevent rolling of the waist band, the front portion is drawn down into a V- 95 shaped conformation as shown in Figure 2, or in a gradual curve as indicated in Figure 4. Referring to Figure 2, in which the front of the elastic band is V-shaped, when in position of repose, the top edge 8 of the webbing is constructed shorter than the bottom edge 9. This 100 may be done by providing a triangular over-lap in the middle as indicated at 10, or by cutting the elastic through at this point and stitching the parts together in divergent relation. When the 105 waist band is stretched by the body, the lateral portions 11 and 12 are pulled out to vertical position and the top edge 8 raised to the plane of the top edge of the rear portion 13 of the waist band. This places the rubber strands 6 110

which are adjacent the top of the waist band under greater tension than those at the bottom of the waist band and effectively prevents the top edge from rolling down over the rest of 5 the waist band.

Figure 4 shows a modification in which the front portion 14 of the waist band when in repose follows a gradual curve. This may be produced by cutting the material of the body 10 portion 2 in the form of a curve at its upper edge and stitching the waist band to it. It is essential, however, that the top edge 15 of the front portion be shorter than the bottom edge 16. This is accomplished by taking a triangular 15 pleat in the middle of the front portion of the waist band as shown at 17, or in any one of several obvious ways. When worn, the inwardly inclined lateral portions of the waist band are diverted to a vertical relation, drawing the top 20 edge of the front portion upwardly into line with the top edge of the back portion, thus stretching the upper rubber strands to a greater extent than the lower rubber strands and thereby preventing outward curling or rolling.

25 Still another form of the invention is shown in Figure 3 in which the front portion of the waist band 18 is straight, that is to say, undeflected in the middle. The non-curl property is imparted to the webbing in this form, by 30 initially stressing the upper rubber strands 6 to a greater extent than the lower strands in the manufacture of the webbing. This natural differential in the tension of the rubber strands in the upper and lower parts of the webbing prevents its rolling, and the difference in tension 35 is increased by the fact that the stretching of the waist band upon the body draws the inclined end portions 19 into a vertical position, further

stressing those rubber strands which are nearest the top.

It is obvious from the above that I have devised the novel construction of pants or bloomers characterized in the first place by the feature 80 that they conform at the waist band and at the leg openings with the contour of the body without creating any fullness in the material of the garment, that the elastic bands at the waist and leg openings is self-ventilating, that the 85 ventilating capacity of the waist and leg bands is automatically varied with the tension of the said bands, and that through means which impart an initial excess of tensioning to the upper rubber strands in the waist bands, any tendency 90 to roll downwardly is inhibited.

What I claim is:

Bloomer or the like having a relatively wide elastic waist band made of a continuous length of elastic material to the lower edge of which a relatively flimsy portion of the garment is stitched all around, said waist band being provided with circumferential elastic rubber warp strands alternating with open mesh courses, the front portion of the waist band when the garment 100 is laid flat being inclined downwardly toward the middle so that the top edge of the inclined portion extends below the top edge of the rear portion and the folded side edges converge toward the top edge, the length of the 105 top edge of the waist band being thus less than the length of the bottom edge thereof when the garment is not worn, but acquiring an equal length when the waist band is stretched about the waist of the wearer so that the top portion 110 of the waist band will be stressed in excess of the bottom portion, to avoid rolling.

HOWARD B. SNADER.
